UNITED STATES PATENT OFFICE

JACOB S. DETRICK, OF BALTIMORE, MARYLAND.

HEADLIGHT CONTROL FOR AUTOMOBILES.

No. 823,163.

Specification of Letters Patent.

Patented June 12, 1906.

Application filed September 9, 1905. Serial No. 277,652.

To all whom it may concern:

Be it known that I, JACOB S. DETRICK, a citizen of the United States, residing in Baltimore, in the State of Maryland, have invented certain new and useful Improvements in Headlight Control for Automobiles, of which the following is a specification.

This invention relates to controlling means for directing searchlights or other lamps on a moving body—such as a vehicle, boat, or the like—and has for its object to provide means for moving the lamp to project its light in a plurality of directions by a member separate from the lamp, but operatively connected therewith.

The invention broadly comprises a controlling-lever operated, preferably, by the foot to move in two different paths and thereby swing the light to project its rays in horizontal directions and to also project its rays at different altitudes in the several horizontal directions to which moved.

In the drawings illustrating an embodiment of my invention, Figure 1 represents the device applied at the front of a motor-car or similar vehicle, the device being shown in side elevation and a portion of the car in section. Fig. 2 shows the device in plan. Fig. 3 is a front elevation of the upright member and lamp. Fig. 4 is a transverse section on the line 4-4 of Fig. 1. Figs. 5 and 6 show in front and side elevation the joint of the connecting-rod with the foot-lever, and Figs. 7 and 8 show in front and side elevation, respectively, the joint between the connecting-rod and an arm secured to the lamp.

The searchlight or lamp 12 is pivotally supported on the upper end of an upright member 13, which is supported to rotate on a vertical axis from a portion of the vehicle, preferably the dashboard 14, by rotating in a socket member 15, fast to the top of the dashboard, and also supported in a socket member 16, secured in the floor 17 of the car. The lamp is shown as having a trunnion-support on the top of the upright 13 by securing on the latter a fork member 18. Pins 19 projecting horizontally from opposite sides of the lamp rest in apertures in the fork members, thereby supporting the lamp to swing on a horizontal axis on the upright 13. The upright is thus supported to swing on a vertical axis, whereby its rotation will cause the lamp to project its rays in any desired direction horizontally, and the lamp can be swung on its trunnion-support so that its rays may

be adjusted to project upward or downward in any of the positions to which the post may be adjusted.

A single member or controlling lever is provided movable in two different paths and so connected with the lamp and post supporting the lamp that movement of the lever in one of said paths will swing the lamp on a vertical axis, while movement of the lever in its other path will swing the lamp on its trunnion-support on a horizontal axis. In the present instance this controlling-lever is placed near the floor of the car 17 in convenient position to be controlled by the foot of the operator. The lever 20 is preferably pivotally mounted on the top of a short spindle 21, that is rotatable in a socket member 22, set into the floor 17, with the bore of the socket arranged vertically. A suitable connection is arranged between the spindle 21 and the post 13, whose axes are substantially parallel, whereby the rocking of the spindle by the foot-lever 20 will oscillate the upright 13 and cause the lamp to be adjusted to either side, as desired. This connection may comprise a chain 23, passing around a sprocket 24 on the upright 13 and a sprocket 25 on the spindle 21. A suitable connection is also provided whereby the swinging of the foot-lever 20 will rock the lamp on its trunnion-support on the upright. This connection is shown as formed of a connecting-rod 26, that is joined to the front end of the foot-lever by a universal joint and is similarly connected with an arm 27, secured to the lamp and extending rearward therefrom. This connection with the foot-lever is shown in Figs. 5 and 6 as formed by having a fork-piece 28, fast on the lower end of the rod 26, between which forks is pivoted a block 29 by a pin 30 passing through a bore in the block and into the fork-arms. The block has another bore at right angles to said bore, through which passes a screw 31, tapped into the front end of the foot-lever 20, the block 29 being arranged to swing on said screw.

At the upper end of the rod 26 is secured a fork-piece 32, between whose arms is pivoted a piece 33. At the rear of the lamp extends an arm 27, to which is suitably secured a clamp 34, and between the end portions of the clamp is pivoted the piece 33 to swing on an axis at right angles with the axis of the joint between the piece 33 and the fork-piece 32. This universal joint at each end of the connecting-rod with the lamp and the foot-

lever is employed because of the change in the relative positions of the lamp and foot-lever caused by the swinging of both members on a vertical axis.

5 The lamp may be provided with means for normally retaining it straight forward. In Fig. 1 a spring 35 is extending between an arm 36, secured on the lower end of the upright 13 and projecting rearward, and the bottom of the floor 17, which spring will be distended when the upright is rocked to either side and return the arm and post to such position when released. The lamp 12 is provided with means for keeping it level, a spring 37 extending between the middle of the fork 18 and the part of the lamp vertically above such part when the lamp is level, as shown in Fig. 3.

By the above construction it will be seen that the lamp may be readily controlled by slight movements of the foot-lever, the side motion or twisting of the lever by the foot serving to direct the rays of the lamp either straight forward or toward either side, as desired, and when so directed a slight rocking of the foot-lever will serve to direct the rays to the roadway either immediately in front of the car or at any distance beyond the same or else to various heights as desired. 30 The springs will serve to return the lamp to normal position directed straight ahead upon the controlling-lever being released.

What I claim is—

1. The combination, in a vehicle, of a rocking upright member, a lamp supported by said rocking member for horizontal movement, a rocking pivotal member located in parallelism with said first rocking member, means connecting the two rocking members, 40 a foot-lever pivoted to said rocking pivotal member for horizontal movement, a connection between said foot-lever and said lamp and comprising a rod having a universal connection with said foot-lever and with said lamp, the organization being such that on the movement of the foot-lever in a vertical plane the lamp will likewise be swung in a similar plane and on the operation of the

foot-lever in a horizontal plane in either direction both of said rocking members will be 50 rocked simultaneously and the lamp swung in a horizontal plane.

2. The combination, in a car, of an upright member arranged to swing on a vertical axis, a supporting member in the floor of the car mounted to swing on a vertical axis, a foot-lever pivoted on the supporting member to swing on a horizontal axis transverse to the car, a connection between the supporting member and the upright member causing the 60 rocking of the supporting member by the foot-lever to rock the upright member, a lamp carried by the upright member to swing on a substantially horizontal axis, and a rod having a universally-movable connection with said lever and also having a universally-movable connection with a portion of the lamp and arranged to cause the rocking of the foot-lever on its support in the several 70 positions of the upright member to swing the lamp on its horizontal axis in the several positions of the lamp to which moved by the upright member.

3. The combination in a car, of a post supported adjacent the front of the car to swing 75 on a vertical axis, a lamp supported by the post to swing on a substantially horizontal axis, a spindle mounted in the floor of the car to swing on a substantially vertical axis, a gear fast on said spindle, a gear fast on said 80 post, a chain engaging said gears, whereby the swinging of the spindle on its vertical axis by the lever will swing the lamp on its vertical axis, a foot-lever pivoted on said spindle to swing on a substantially horizontal axis, a rod having a universally-movable connection with said lever, and also having a universally-movable connection with said lamp, whereby the swinging of the lever on the spindle will swing the lamp on its 85 horizontal axis.

JACOB S. DETRICK.
